UNITED STATES PATENT OFFICE.

GEORGE T. LEWIS, OF CHERRYVALE, KANSAS.

FLUID-CURRENT CONVEYER.

Application filed March 21, 1922. Serial No. 545,537.

To all whom it may concern:

Be it known that I, GEORGE T. LEWIS, a citizen of the United States, residing at Cherryvale, in the county of Montgomery and State of Kansas, have invented certain new and useful Improvements in Fluid-Current Conveyers, of which the following is a specification.

My invention relates to conveyers, and 10 has particular reference to a fluid conveyer, designed for conveying finely powdered coal, in suspension in an air blast or current.

An important object of the invention is 15 to provide apparatus of the above mentioned character which is so constructed that clogging of the same by the accumulation of the powdered coal, is prevented; that the valves may be cleaned individually 20 without shutting off the air blast or current in the main pipe, thereby not interfering with other burners connected on the main pipe; that the valves are so constructed that they are cleaned, to a considerable extent, by opening and closing the same; 25 that the valves are cleaned automatically, to a certain extent, by being disposed at an angle to the direction of travel of the powdered coal, and projecting into such path 30 of travel; that the valves may be opened and closed from a low elevation; and that the valves may be conveniently manipulated for regulating the volume of powdered coal conveyed to the burners.

35 Other objects and advantages of the invention will be apparent during the course of the following description.

In the accompanying drawings forming a part of this specification and in which 40 like numerals are employed to designate like parts throughout the same,

Fig. 1 is a plan view of an apparatus embodying my invention,

Fig. 2 is a central horizontal section 45 through the same,

Fig. 3 is a transverse vertical section through the main pipe, showing the valve structure in elevation, and

Fig. 4 is a side elevation of the crank 50 and associated elements.

In the drawings, wherein for the pur-

pose of illustration is shown a preferred embodiment of my invention, the numeral 5 designates a main pipe, which preferably has a substantial diameter, such as 55 twelve inches or more. This main pipe may be horizontally arranged, and powdered coal, suspended in air, is forced longitudinally through the main pipe 5, by a rotary blower, of suitable construction. The 60 arrows in Fig. 2 indicate the direction of travel of the powdered coal.

The numeral 6 designates a valve structure as a whole, which constitutes means for withdrawing the powdered coal, suspended 65 in the air blast, from the main pipe. There are a number of these valve structures mounted on the main pipe, at spaced intervals, depending from the number of burners, furnaces or the like, which are fed 70 from the main pipe. A detail description of one valve structure will of course suffice.

The valve structure embodies a casing 7, which is preferably cylindrical, and this casing is rigidly mounted upon a base or 75 saddle 8, which is curved in cross-section. The saddle 8 has its ends apertured for receiving the ends of a U-shaped strap 8', surrounding the main pipe 5. The ends of this strap are cylindrical and screw 80 threaded to receive nuts 9'. The saddle is thus clamped to the main pipe.

The tubular cylindrical casing 7 is arranged at an obtuse angle to the exterior of the main casing 5 and has an inner projection 8'', extending into the main pipe, at an angle to the direction of travel of the powdered coal, as shown. The forward end of the projection 8'' is closed, by a head 9'' or the like, and this projection is 90 provided upon its forward side with an opening 10, through which the powdered coal may pass.

Rotatably mounted within the tubular casing 7 is a tubular valve 11, the forward 95 end of which is closed by a head 12, contacting with the head 9''. The tubular valve is provided upon its forward side with an opening 13, adapted to be moved into and out of registration with the opening 10. The rear end of the tubular valve 11 is open, as shown.

A housing 14 is preferably formed integral with the casing 7 and is spaced therefrom. This housing extends for less than half of the circumference of the casing 7, 5 as shown. The function of the housing 14 is to rigidly and securely connect the portions of the casing 7, which are separated by an annular opening 15, within which is pivotally mounted a ring or band 16, rigidly mounted upon the tubular valve 11. A crank 17 is carried by the band 16, and extends upwardly from the housing 14, and this crank carries a grooved segment 18, engaged by a rope 19 or other flexible 15 element. It is thus seen that the ends of the rope 19 will extend downwardly in convenient reach of the operator, who may thus turn the crank 17 in either direction, for partly or wholly closing the opening 10. The crank 17 has a longitudinal slot 17', providing spaced slightly resilient arms 18', which are integral with the ends of the band 16. The arms 18' are connected by bolts 19', as shown. It is obvious that 25 the ring 16 may be contracted and clamped to the tubular valve 11 by manipulation of the bolts 19'.

The rear end of the tubular casing 7 is preferably screw threaded, as shown at 20, 30 for engagement with a coupling 21, preferably having a laterally extending branch 22, connected with a pipe 23, which leads to the fire, burner, furnace or the like. When this branch 22 is employed, I provide a plug 24, 35 having screw threaded engagement within the rear end of the coupling 21. By removing the plug 24, a straight and uninterrupted passage is afforded to the interior of the tubular valve, so that a suitable instrument 40 may be inserted therein, to clean the interior of the tubular valve. Prior to cleaning, the tubular valve may be turned to the closed position.

The coupling 21 may be dispensed with, 45 and the pipe 23 connected directly with the rear end of the casing 11. If this is done, the pipe 23 must be disconnected from the casing 11, prior to the insertion of a tool into the tubular valve 11, for cleaning.

50 In the operation of the apparatus, the air laden with the powdered coal, is blown in the direction of the arrows, Fig. 2, through the main pipe 5. The tubular valve 11, being wholly or partly opened, a certain amount of powdered coal will pass through the openings 10 and 13 and be forced through the tubular valve, into and through the pipe 23, to the fire, burner or furnace.

It is to be understood that the form of my 60 invention herewith shown and described is to be taken as a preferred example of the same, and that various changes in the shape, size and arrangement of parts may be resorted to without departing from the spirit of my invention, or the scope of the subjoined claims.

Having thus described my invention, I claim:

1. The combination with a main pipe through which powdered coal is blown, of a valve casing mounted upon the pipe and 70 having its forward end projecting into the main pipe, the forward side of the casing within the main pipe being provided with an opening, a housing formed upon the outer portion of the casing exteriorly of the main pipe, said casing being provided within the housing with an annular opening dividing the same into sections, a tubular valve rotatable within the casing and provided in its forward end with an 80 opening cooperating with the opening in said casing, a crank having a band arranged within the annular opening and receiving the tubular valve and clamped thereto, means to turn the crank, and an outlet pipe connected 85 with the casing.

2. The combination with a main pipe through which powdered coal or the like is blown, of a valve casing mounted upon the main pipe and having an inclined forward 90 portion projecting into such main pipe, such forward portion being provided upon its forward side with an opening whereby the powdered coal in the main pipe may be passed into the valve casing, a tubular valve rotatable within the valve casing and having an opening upon its side near its intake end to cooperate with the first named opening, said tubular valve having its outlet end open, said valve casing projecting outwardly beyond the rear end of the tubular valve, an element mounted upon the tubular valve between the ends of the valve casing and projecting laterally from the valve and adapted to turn it, and a device connected with the 105 outer end of the tubular valve casing to normally close the same and having a removable element for affording ready access to the outer end of said tubular valve casing.

3. In a fluid conveyer, a main pipe having 110 an opening formed in its side wall, a tubular valve casing extending through the opening into the main pipe and provided upon one side with an opening, a housing connected with the inner and outer sections of the tubular valve casing and spaced therefrom, the tubular valve casing having an annular opening 115 formed therein which is arranged between the ends of the housing, a tubular valve within the valve casing, a ring mounted upon the 120 tubular valve within the annular opening, an element connected with the ring to turn it, and an outlet conduit connected with the tubular valve casing.

4. In a fluid conveyer, a main pipe having 125 an opening formed therein, a tubular valve casing extending through the opening into the pipe and provided within said pipe with an opening, said tubular valve casing being provided exteriorly of the main pipe with an 130

annular opening, an element rigidly connecting the inner and outer portions of the housing formed by said annular opening, a crank provided with a longitudinal slot within the valve casing and extending through the ring, means to secure the valve casing to the main pipe, and an outlet pipe 10 connected with the valve casing.

5 forming spaced arms, a ring having its ends secured to said spaced arms, means to draw the arms together, a tubular valve rotatable

In testimony whereof I affix my signature,

GEORGE T. LEWIS
